(57) **CLAIM**

The ornamental design for an earphone component, as
shown and described.

DESCRIPTION

Earphone components

1.1 is a front elevation view of an earphone component
showing our new design in a first embodiment;
1.2 is a back elevation view thereof;
1.3 is a left side elevation view thereof;
1.4 is a right side elevation view thereof;
1.5 is a top plan view thereof;
1.6 is a bottom plan view thereof;
4.1 is a front elevation view of an earphone component
showing our new design in a second embodiment;
4.2 is a back elevation view thereof;
4.3 is a left side elevation view thereof;
4.4 is a right side elevation view thereof;
4.5 is a top plan view thereof;
4.6 is a bottom plan view thereof; and
4.7 is a perspective view thereof.
